BRUSH ELEMENT OF THE STRIP TYPE

Robert W. Vose, West Springfield, Mass., assignor
to The Fuller Brush Company, Hartford, Conn.,
a corporation of Connecticut

Application December 19, 1951, Serial No. 262,358

7 Claims. (Cl. 15—205)

1

The invention relates to a brush element of the strip type wherein the brush fibers are held by a metallic strip and are arranged in longitudinally spaced tufts. While not necessarily so limited, a brush element embodying the invention is particularly adapted for winding on a central core or drum to form a cylindrical brush.

More particularly, the invention relates to a brush element having the general characteristics of that set forth in the copending application of Alfred L. Le Febvre, Robert W. Vose and Ernest D. Hargreaves, Serial No. 93,942, filed May 18, 1949, for Brush Element of the Strip Type, now Patent No. 2,616,111, dated November 4, 1952. The said patent discloses a brush element comprising a plurality of similar longitudinally spaced tufts of fibers each having a rear portion and a projecting front portion, and a single longitudinal sheet metal member bent to provide a rear wall and to provide two oppositely disposed side walls which side walls are shaped to form a plurality of pairs of oppositely disposed mating socket sections longitudinally spaced to respectively receive the inner portions of the said fiber tufts.

One object of the present invention is to provide a brush element similar to that set forth in the said patent but so constructed as to enable the socket sections to more firmly engage the corresponding tufts.

Another object of the invention is to provide a brush element as last above set forth and provided with interengaging means on the side walls of the sheet metal member for preventing separation of the said side walls and for thus holding the socket sections in firm engagement with the tufts.

A further object of the invention is to provide various details of construction and arrangement which enable the foregoing more general objects to be attained.

In the drawing I have shown in detail a preferred embodiment of the invention, but it will be understood that various changes may be made from the construction shown, and that the drawing is not to be construed as defining or limiting the scope of the invention, the claims forming a part of this specification being relied upon for that purpose.

Of the drawing:

Fig. 1 is a side view of a brush element of the strip type embodying the invention.

Fig. 2 is a horizontal sectional view taken along the line 2—2 of Fig. 1.

Fig. 3 is a view similar to Fig. 1 but showing

the brush element bent to conform to a cylindrical surface such as the surface of a drum.

Fig. 4 is a transverse vertical sectional view taken along the line 4—4 of Fig. 1.

5 Fig. 5 is a transverse vertical sectional view taken along the line 5—5 of Fig. 1.

Fig. 6 is a transverse vertical sectional view taken along the line 6—6 of Fig. 1.

Fig. 7 is a fragmentary longitudinal sectional view taken along the line 7—7 of Fig. 6.

Fig. 8 is a fragmentary longitudinal sectional view taken along the line 8—8 of Fig. 6.

10 Fig. 9 is a view similar to Fig. 8 but showing the increased curvature resulting from the bending of the brush element as shown in Fig. 3.

The brush element as shown comprises a longitudinal sheet metal member 10 bent to provide a channel having a rear wall and having two oppositely disposed side walls. The side walls are 20 shaped to provide a plurality of pairs of oppositely disposed mating socket sections 12 and 14 which cooperate to provide sockets and which are uniformly spaced longitudinally. Engaged with in the several sockets and projecting forwardly therefrom are tufts 16, 16 formed of suitable fibers. The term "fibers" is herein used in a generic sense and is intended to include vegetable fibers, or bristles or other animal fibers, or synthetic fibers, or metallic wires, or any other suitable filaments or brush material.

30 The socket sections 12 and 14 of each pair are in firm pressed engagement with the corresponding fiber tuft 16 and the said socket sections of each pair are mutually unobstructed to enable them during final bending to move toward each other to the extent permitted by their engagement with the tuft. This insures firm engagement of the socket sections with the tufts notwithstanding minor variations in the sizes of the tufts.

35 In describing the socket sections of each pair as mutually unobstructed, it is meant that neither of them has any portion which would engage or obstruct the other in its movement into firm engagement with the tuft. Preferably the 40 adjacent portions of the socket sections of each pair transversely overlap when in their final positions, thus insuring the complete enclosure of the corresponding fiber tuft.

45 Between the socket sections 12 and 14, the side walls of the sheet metal channel member comprise transversely extending parts 18 and 20 constituting pairs of socket connecting portions, these connecting portions being preferably located approximately midway between the front 55 of the channel and the rear wall thereof.

Between the socket sections 12 and 14, the side walls of the channel member are formed with notches 22, 22 which extend rearwardly to the inner forward edges of the said oppositely inclined portions 18 and 20. Openings or notches 24, 24 are provided in the channel member at the rear, these notches registering with the notches 22, 22 and interrupting the rear wall and also interrupting the rear portions of the side walls. By reason of the interruption of the rear wall, longitudinally spaced rear wall portions 26, 26 are provided respectively behind the sockets and the tufts. These notches 24, 24 extend forwardly to the outer rearward edges of the oppositely inclined portions 18 and 20. It will be seen that, by reason of the notches 22, 22 at the front and the notches 24, 24 at the rear, the said portions 18 and 20 constitute the sole connections between the pairs of socket sections 12 and 14. These connecting portions 18 and 20 are relatively thin and they can be readily bent rearwardly, as for instance when the brush element is wound on a drum as indicated in Fig. 3. While it is essential that bending shall occur only at the connecting portions of the strip, it is desirable to avoid excessive flexibility and this is brought about by placing the connecting portions 18 and 20 in oppositely inclined positions as shown, the said parts diverging in the rearward direction.

The oppositely inclined connecting portions 18 and 20 are preferably longitudinally arched at 28, 28 as clearly shown in Figs. 7 and 8. There is little or no arching at the inner edges of the said parts, but the extent of arching progressively increases from the inner edges thereof to the outer edges thereof. For a reason to be herein-after set forth, the arching is preferably in forward directions.

A longitudinal core or retaining wire 30 is preferably provided which extends throughout the length of the brush element. This wire is within the channel and it is in front of the rear wall portions 26, 26 and behind the inner zones of the oppositely inclined connecting portions 18 and 20. The bunches of fibers constituting the several tufts 16, 16 are looped around the wire 30 as clearly shown in Figs. 1 and 4, the wire thus serving to retain the fibers in place. The several parts are so related that the looped portions of the fibers engage the rear wall portions 26, 26. As has been stated, the fiber tufts are firmly engaged by the socket sections 12 and 14. The wire 30 engages the connecting portions 18 and 20 and the said portions serve not only to prevent forward movement of the wire but also to hold the wire in central position.

As has been stated, the socket sections 12 and 14 are mutually unobstructed so that during final bending they can move toward each other to the extent permitted by the corresponding fiber tuft, the socket sections being thus in firm pressed engagement with the tuft. In order to retain the said socket sections of each pair in their said pressed relationship with the tuft, one of them is provided with at least one transversely extending tab, which partly embraces and holds the other section of the pair. As shown, there are two tabs 32 and 34 formed on the edge portions of the socket section 12, these tabs partly embracing the opposite socket sections 14. It will be seen that these tabs 32 and 34 prevent separation of the two sections and thus hold them in firm engagement with the fiber tuft.

Preferably the tabs 32 and 34 are tapered and

have their smallest depths at their projecting ends. In order to additionally resist any relative movement between the two socket sections 12 and 14, the side wall adjacent each socket section 14 is provided with portions 36 so positioned as to be engaged by the rear edges of the tabs 32 and 34 during final bending of the sheet metal member 10. This engagement is clearly shown in Figs. 1 and 5. It will be seen that there is a mutual indentation between each portion 36 and the corresponding tab 32 or 34.

Preferably, in order to further assist in preventing any separation of the side walls and more particularly of the socket sections, one connecting portion of each pair is provided at the front with a transversely extending tab which engages the other connecting portion of the pair at the front thereof. As shown, the connecting portion 20 of each pair is provided with a transversely extending tab 38 which engages with the front of the other connecting portion 18. The extreme end portion of each tab is preferably bent rearwardly as shown in Fig. 6 to more effectively engage the portion 18.

It will be observed that the tabs 32 and 34 are on the socket section 12 of one side wall and that the tab 38 is on the connecting portion 20 of the opposite side wall, the said tabs 32 and 34 and the said tabs 38 extending transversely in opposite directions. The described arrangement of the tabs facilitates the formation of the sheet metal blank for the channel, as there would not be sufficient metal for the said tabs 32 and 34 and the said tabs 38 if all of the tabs were at the same side.

During brushing action there is a tendency for the tuft fibers to move inwardly in their respective sockets, the result being that the inner looped portions of the bunches of fibers tend to move longitudinally along the wire. This tendency is effectively resisted by the described firm pressed engagement of the socket section with the fibers, but for additionally resisting the said tendency means additional to the sockets are preferably provided which are so positioned as to prevent any longitudinal movement of the looped portions of the fibers. This means may be variously formed, but preferably and as shown it comprises centrally located tabs 40, 40 projecting forwardly from the rear wall portions 26, 26. There are two tabs 40, 40 at the opposite sides of each fiber loop as clearly shown in the right portion of Fig. 1. Thus the looped portions of the fibers are closely held and confined by the rear wall portion 26 and by the tabs 40, 40. The tabs 40, 40, preferably engage the wire 30 at the rear thereof, the wire being thus firmly held between the tabs and the connecting portions 18 and 20.

Fig. 3 is similar to Fig. 1 but shows the brush element bent to conform to a suitable curvature such as the curvature of a drum. All bending has taken place at the connecting portions 18 and 20 and bending has been facilitated by the arching of the said portions at 28, 28. During bending the inner forward zones of the connecting portions are under tension and the outer rearward zones of the said connecting portions are under compression. There is no additional arching at the zones under tension but there is substantial additional arching at the zones under compression. The arched compression portions 28, 28 yield during bending, the arching being increased as will be observed by comparing Fig. 8 with Fig. 9. The portions 28, 28 are arched forwardly and the increased arching does not interfere with the wire 30. Inasmuch as the outer

compression zones freely yield, there is no stretching of the inner tension zones, and there is therefore no tendency to distort or open the sockets. The tabs 38, 38 are particularly useful in retaining the two connecting portions 18 and 20 in proper relationship during bending.

Preferably the centers of bending of the connecting portions 18 and 20 are spaced from the rear wall portions 26 at least as far as is the center of the wire 30, and the centers of bending 10 may advantageously be spaced slightly forwardly of the center of the wire. Thus when the brush element is bent as shown in Fig. 3, there is no tendency to stretch the wire 30. If the centers of bending were at the rear of the center of the wire, there would be a tendency to stretch the wire during bending and bending would therefore be resisted by the resulting tension in the wire.

The invention claimed is:

1. A brush element of the strip type comprising in combination, a plurality of similar longitudinally spaced tufts of fibers each having a rear portion and a projecting front portion, and a single longitudinal sheet metal member bent to provide a rear wall and to provide two oppositely disposed side walls which side walls are shaped to form a plurality of pairs of oppositely disposed mating socket sections longitudinally spaced to respectively receive the said inner portions of the fiber tufts which socket sections of each pair are in firm pressed engagement with the said inner portion of the corresponding tuft, the said socket sections of each pair having their inner edge portions out of transverse register with each other with the result that the said sections are mutually unobstructed to enable them to move toward each other to the extent permitted by their said engagement with the corresponding tuft and one socket section of each pair having a transversely extending tab thereon which partly embraces the other socket section of the pair to prevent separation of the two sections.

2. A brush element of the strip type comprising in combination, a single longitudinal wire extending throughout the length of the brush element, a plurality of similar longitudinally spaced tufts of fibers with the fibers of each tuft looped at the rear around the said wire and projecting at the front, and a single longitudinal sheet metal member bent to provide a rear wall behind the wire and to provide two oppositely disposed side walls which side walls are shaped to form a plurality of pairs of oppositely disposed mating socket sections at the front of the wire and longitudinally spaced to respectively receive portions of the said looped fiber tufts which socket sections of the said pairs are in firm pressed engagement respectively with the last said portions of the said tufts, the said socket sections of each pair being mutually unobstructed to enable them to move toward each other to the extent permitted by their said engagement with the corresponding tuft and one socket section of each pair having two transversely extending tabs thereon which partly embrace the other socket section of the pair to prevent separation of the two sections.

3. A brush element of the strip type comprising in combination, a single longitudinal wire extending throughout the length of the brush element, a plurality of similar longitudinally spaced tufts of fibers with the fibers of each tuft looped at the rear around the wire and project-

ing at the front, and a single longitudinal sheet metal member bent to provide a rear wall behind the wire and to provide two oppositely disposed side walls which side walls are shaped to form a plurality of pairs of oppositely disposed mating socket sections at the front of the wire and longitudinally spaced to respectively receive portions of the looped fiber tufts which socket sections of the said pairs are in firm pressed engagement with the last said portions of the said tufts, the said socket sections of each pair being mutually unobstructed to enable them to move toward each other to the extent permitted by their said engagement with the corresponding tuft and one socket section of each pair having a transversely extending tab thereon which tab partly embraces the other socket section of the pair to prevent separation of the two sections and which tab also engages 20 at its rear edge with a portion of the opposite side wall to additionally resist relative movement between the two socket sections.

4. A brush element of the strip type comprising in combination, a single longitudinal wire extending throughout the length of the brush element, a plurality of similar longitudinally spaced tufts of fibers with the fibers of each tuft looped at the rear around the wire and projecting at the front, and a single longitudinal sheet metal member bent to provide a rear wall behind the wire and to provide two oppositely disposed side walls which side walls are shaped to form a plurality of pairs of oppositely disposed mating socket sections at the front of the wire and longitudinally spaced to respectively receive portions of the said looped fiber tufts which socket sections of the said pairs are in firm pressed engagement respectively with the last said portions of the said tufts, the said socket sections of each pair being mutually unobstructed to enable them to move toward each other to the extent permitted by their said engagement with the corresponding tuft and one socket section of each pair having two transversely extending tabs thereon which tabs partly embrace the other socket section of the pair to prevent separation of the two sections and which tabs also engage at their rear edges with portions of the opposite side wall to additionally resist relative movement between the two socket sections.

5. A brush element of the strip type comprising in combination, a single longitudinal wire extending throughout the length of the brush element, a plurality of similar longitudinally spaced tufts of fibers with the fibers of each tuft looped at the rear around the said wire and projecting at the front, and a single longitudinal sheet metal member bent to provide a rear wall behind the said wire and to provide two oppositely disposed side walls which side walls are shaped to form a plurality of pairs of oppositely disposed mating socket sections at the front of the said wire and longitudinally spaced to respectively receive and firmly engage portions of the said looped fiber tufts, the said sheet metal member being provided with front notches in the side walls between the socket sections and being provided with registering rear notches in the rear wall and in the side walls with pairs of closely adjacent oppositely inclined connecting portions between the said notches one of which connecting portions of each pair has a transversely extending tab thereon engaging the other connecting portion of the pair at the front thereof.

6. A brush element of the strip type comprising in combination, a plurality of similar longitudinally spaced tufts of fibers each having a rear portion and a projecting front portion, and a single longitudinal sheet metal member bent to provide a rear wall and to provide two oppositely disposed side walls, which side walls are shaped to form a plurality of pairs of oppositely disposed mating socket sections longitudinally spaced to respectively receive the said inner portions of the fiber tufts which socket sections of each pair are in firm pressed engagement with the said inner portion of the corresponding tuft and which socket sections of each pair are mutually unobstructed to enable them to move toward each other to the extent permitted by their said engagement with the corresponding tuft and one socket section of each pair having two transversely extending tabs thereon which partly embrace the other socket section of the pair to prevent separation of the two sections, the said sheet metal member being provided with front notches in the side walls between the socket sec-

tions and being provided with registering rear notches in the rear wall and in the side walls with pairs of closely adjacent oppositely inclined connecting portions between the said notches one of which connecting portions of each pair has a transversely extending tab thereon engaging the other connecting portion of the pair at the front thereof.

7. A brush element of the strip type as set forth in claim 6, wherein the said tabs on the socket sections and the said tabs on the connecting portions are on opposite side walls and extend in opposite directions.
